UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

ELECTRICAL TRANSMISSION OF PICTURES.

Application filed October 19, 1926. Serial No. 142,734.

My invention relates to the electrical transmission of pictures and an object of my invention is the provision of improved methods and means for the rapid and efficient 5 transmission of pictures by electrical means.

My invention will be better understood from the following description taken in connection with the accompanying drawing, and its scope will be pointed out in the appended 10 claims.

Referring to the drawings, Figs. 1 and 2 are a diagrammatic representation respectively of a transmitting apparatus and a receiving apparatus embodying my invention; 15 Fig. 3 is a diagram similar to Fig. 2 but drawn to a larger scale; and Figs. 4, 5 and 6 are modifications thereof.

The picture to be transmitted may be an ordinary still picture, a moving picture, or a 20 view, and by the term picture as used throughout this description and in the claims I intend to include all forms of pictures, drawings, printed pages and views of either still or moving objects. In Fig. 1 I have chosen 25 to illustrate my invention being used to transmit a scene or view 1 of two moving characters. In front of the scene is the apparatus for scanning the picture and producing electrical variations corresponding with the variations of the picture as determined by the unit 30 areas thereof. As shown, it comprises a hollow cylinder 2 having a series of lenses 3 mounted thereon and rotated by an electric motor 4, the construction of the cylinder being shown more clearly in the receiver shown 35 by Fig. 3. The lenses 3 are identical in construction and are mounted in the wall of the hollow cylinder in a spiral. Within the cylinder and behind the lenses at the focal point 40 thereof is shown a group of four small mirrors 5 which are arranged each to reflect a light beam from a different unit area of the picture into the window of one of the four photo-electric cells 7.

The arrangement is such that as each lens 45 passes the group of mirrors each photo-electric cell receives light from a narrow vertical band or strip of unit areas of the view. Thus, with the apparatus shown, each lens as 50 it passes the mirrors sends four beams of light

to the photo-electric cells corresponding to the illumination of unit areas in four parallel vertical strips or bands of the view. In one revolution of the cylinder the entire view will have been covered. In accordance with 55 present practice in exhibiting moving pictures the cylinder may be operated at a speed of approximately sixteen revolutions per second. If, however, a still picture is to be transmitted and is to be received on a light 60 sensitive film or paper instead of being thrown on the screen 12 to be observed, a slower speed may suffice. I have shown my invention applied to wireless transmission 65 wherein each photo-electric cell 7 is connected to a device 8 which may include means for amplifying the impulses received thereby and for producing and modulating a radio carrier wave which may be broadcast from antennae 9. The wave lengths of the carrier 70 waves produced by each device 8 will be separated by a suitable interval to facilitate tuning of the receivers used therewith. It is to be understood, however, that my invention is not limited to wireless operation since the cells 75 may control the current flowing through conducting wires.

The receiver illustrated in Figs. 2 and 3 is shown comprising an image-receiving member or screen 12, a hollow cylinder 13 having 80 a series of lenses 14 set therein in a spiral similar to the cylinder 2 of the transmitter shown in Fig. 1 and a driving motor 15. By suitable means, examples of which are well known in the art, motors 4 and 15 are caused 85 to run in synchronism, hence the cylinders 2 and 13 rotate synchronously. Within the cylinder 13 and at the focal point of the lenses 14 are four small mirrors 16 similar to mirrors 5 of Fig. 1. At a point opposite the end of 90 the cylinder 13 are four oscilloscopes 18 having small mirrors 19 and in a suitable position to throw light on these mirrors I provide suitable means, shown in the drawing as comprising four light sources 20. A light beam 95 from each of these sources is condensed by a suitable lens 21 on one of the oscilloscope mirrors from whence it is reflected to another lens 22 and condensed on one of the four mirrors 16. The four light beams re- 100

flected from each of these pass simultaneously through the same lens 14 and produce four spots of light on the screen. As the cylinder 13 rotates in the direction indicated by the arrow these four spots of light travel down across the screen in four parallel paths or bands 23. The instantaneous brightness of each of the four spots of light thrown on the screen is controlled respectively by the four oscilloscopes. For energizing these oscilloscopes I have shown four carrier wave receiving sets 25 each having a receiving loop 26 and tuned to receive the carrier waves sent out by the respective sending devices 8. The arrangement is such that as the first lens 14 of the spiral passes the group of mirrors 16 four spots of light are directed on the screen which as the cylinder rotates trace four vertical bands of light across one end of the screen. The next lens being slightly offset in an axial direction causes another four spots to trace another four vertical bands next adjacent the first four and so on for each lens of the series, the light spots from the last lens tracing bands across the opposite end of the screen. The cylinder 13 rotates in synchronism with the cylinder 3 at the sending station and as each oscilloscope varies the amount of light directed on one of the four mirrors 16 in response to the light received by the correspondingly arranged photo-electric cell 7 at the sending station an image of the scene 1 is projected on screen 12. By employing a plurality of small mirrors 16 together with a corresponding number of light-controlling means whereby a plurality of light spots simultaneously sweep across the screen a much more efficient illumination of the screen is obtained. This plurality feature enables me to employ a fewer number of rotating lenses and lenses of a correspondingly larger diameter than would be the case were a single mirror used and a single spot projected by each lens. As a result, the illumination of the screen increases not merely in direct proportion to the number of small mirrors 16 but at a more rapid rate being approximately in proportion to the square of the number of mirrors.

In the modified form of receiver shown in Fig. 4 the light spots are reflected on the screen from a series of rotating mirrors instead of being projected thereon by lenses. The disk 30 connected to be driven by the motor 31 in synchronism with the cylinder at the sending station has mounted on its periphery a series of mirrors 32. Starting for example with mirror 33 at one end of the series each succeeding mirror is inclined slightly more than the preceding mirror until the last mirror 34 of the series is reached. Between the mirror disk 30 and the screen 12 is the lens 35 and between the lens and the screen are the four small mirrors 36 corre-

sponding to the four mirrors 16 of Figs. 2 and 3. As in those figures also four oscilloscopes 18 having mirrors 19 control the amount of light received from the four sources 20 through condensing lenses 21 and 22. I have shown the mirror disk 30 rotatable on a vertical axis and the four small mirrors arranged vertically, hence the four light spots traverse the screen horizontally instead of vertically as in the preceding form, the four beams being simultaneously reflected by each successive mirror as it comes into position.

In the modified form shown in Fig. 5, I have shown a motor-driven mirror disk like that in Fig. 4 but in this case the four small mirrors 36 are located at one side of the line of projection from the rotating mirrors to the screen. The four light beams from the four small mirrors are passed through the lens 38 and are simultaneously reflected by each successive mirror 32 as it comes into position. As before, the four light beams are controlled respectively by the four oscilloscopes 18. The same advantage in illumination efficiency may also be obtained with the rotating mirrors as with the rotating lenses for similar reasons. In the sending apparatus a rotating disk having reflecting mirrors such as shown in Fig. 4, or in Fig. 5, may be used if desired instead of the rotating cylinder of lenses shown in Fig. 1.

In the modification illustrated in Fig. 6, I have shown diagrammatically a receiving arrangement whereby the light beams are controlled by a form of Kerr cell, the beams being caused to traverse the image receiving member by a mirror arrangement like that shown in Fig. 5. Light from a single source, such for example as an arc light 40, after passing through the condensing lens 41, passes on through the first Nicol prism 42, the cell 43, the second Nicol prism 44 turned at right angles to the first prism and the lens 45. From the lens 45 the rays converge and are reflected by the respective mirrors 32 of the disk 30 to the image receiving member or screen 12. I have shown the cell 43 diagrammatically as comprising the glass vessel 47 containing a suitable liquid such as nitro-benzol in which are immersed seven pairs of spaced electrodes 48. The plates forming the electrodes are arranged so that light rays may pass through the space separating the plates of each pair and thus be subject to the electrostatic stress therein. The pairs of electrodes are so arranged relative to each other that the seven beams when directed upon the screen 12 form seven spots of light and, as the disk 30 rotates, trace seven bands of light across the screen instead of four as in the preceding modifications. The several bands may just meet or, if desired, may slightly overlap. One electrode of each pair 48 has a separate connection 49 extending

without the cell while the remaining electrodes are connected together for convenience by a single connection 50. The seven pairs of electrodes are thus adapted to be independently controlled for example from a corresponding number of receivers 25 or from a radio carrier current of seven channels of the Hammond type. The two prisms 42 and 44 are arranged to produce planes of polarization at right angles to each other so that when there is no field between the electrodes the light beams are shut off but when a field is applied to any of the pairs of electrodes the plane of polarization is thereby twisted so that light is let through at that point. Seven independently varying beams of light thus simultaneously traverse the screen with the passage of each mirror.

The advantages of the multiple beam system illustrated by rotatable lenses and rotating mirrors applies equally to other well known methods of analyzing the picture such as vibrating mirrors. A reduction of the rate of vibration to one-fourth, as shown, makes it possible to use a large mirror and thus gain in total illumination by increase of the brilliancy of each light spot in addition to the direct gain by using four beams instead of one.

It is to be understood that the terms "light" and "illumination" as used in the description and claims are not restricted to those rays which constitute the visible portion of the spectrum but apply equally well to the invisible portions of the spectrum, for under certain conditions it may be more desirable to make extensive use of the invisible rays in the transmitting apparatus and this also may be done in the receiving apparatus, particularly if it is constructed to reproduce the picture photographically instead of visually.

What I claim as new and desire to secure by Letters Patent of the United States, is:

1. The method of transmitting pictures which comprises simultaneously scanning a group of adjacent bands of unit areas, successively scanning adjacent groups of said bands, and producing electric currents corresponding with the tones of the picture indicated by the light emitted by said unit areas.

2. The method of transmitting pictures which comprises simultaneously scanning a group of bands of adjacent unit areas, successively scanning different groups of said bands, and producing electrical variations corresponding with the variations of the picture as indicated by the light emitted from said unit areas.

3. In picture transmission, the method of receiving a transmitted picture on an image receiving member which comprises scanning the member simultaneously with a group of adjacent light beams, independently varying the intensity of the beams, and successively scanning adjacent areas of said member with said group of light beams.

4. In picture transmission, the method of receiving a transmitted picture on an image receiving member which comprises scanning the member simultaneously with a group of light beams forming a group of adjacent light spots on the member, independently varying the intensity of each of the light beams, and successively scanning adjacent areas of said member with said group of light beams.

5. The method of transmitting a picture to an image receiving member at a distant point which comprises simultaneously scanning a group of adjacent bands of unit areas, successively scanning different groups of said bands, producing electrical variations corresponding to variations in the color of said unit areas, scanning the receiving member by a plurality of light beams, and varying the several light beams in accordance with the respective electrical variations.

6. Apparatus for the transmission of pictures comprising means for successively scanning adjacent groups of bands of unit areas of the picture to be transmitted, and means for producing electrical variations corresponding to the variations of the picture as successively determined simultaneously by the unit areas of said groups.

7. Apparatus for the transmission of pictures comprising means for successively scanning adjacent groups of bands of unit areas of the picture to be transmitted, and a plurality of photo-electric devices arranged to receive light simultaneously from the different single unit areas of one of said groups.

8. Apparatus for the transmission of pictures comprising means for successively scanning adjacent groups of bands of unit areas of the picture to be transmitted, a plurality of photo-electric devices arranged to receive light respectively from said unit areas and electrical transmitting means respectively responsive to said devices.

9. Apparatus for the transmission of pictures comprising an image receiving member, means for simultaneously moving a group of adjacent light beams over a part of said member, means for causing said group of light beams to be moved successively over different parts of said member, and means for controlling the intensity of the respective light beams.

10. Apparatus for the transmission of pictures comprising an image receiving member, a plurality of electrical receiving means, means for projecting a plurality of adjacent beams of light on said member, means for controlling the intensity of said beams respectively by said receiving means, and means for causing said beams simultaneously to sweep across a part of said image receiving member and for causing said beams to be successively swept across different parts of said member.

11. Apparatus for the transmission of pic-

tures comprising an image receiving member, a receiver comprising a plurality of means for independently receiving electrical variations, means for producing a plurality of adjacent light beams, means for controlling the intensity of said beams respectively by said receiving means, and a rotatable member having a plurality of light directing units, each successive unit being arranged to project simultaneously said light beams on 10 a different part of said member.

In witness whereof, I have hereunto set my hand this 18th day of October 1926.

ERNST F. W. ALEXANDERSON.
